UNITED STATES PATENT OFFICE.

FRANZ JOHN HEIBERGER, JR., OF WASHINGTON, DISTRICT OF COLUMBIA, AND
MARGARET CARTER STUART, OF RICHMOND, VIRGINIA.

SEARCH OR HEAD LIGHT SHIELD.

1,145,414.

Specification of Letters Patent. Patented July 6, 1915.

Application filed March 24, 1914. Serial No. 826,959.

To all whom it may concern:

Be it known that we, FRANZ J. HEIBERGER, Jr., of the city of Washington, in the District of Columbia, and MARGARET CARTER STUART, of Richmond, in the county of Henrico and State of Virginia, have invented certain new and useful Improvements in Search or Head Light Shields, of which the following is a specification.

Our invention relates to the art of search lights or head lights such as are particularly used on automobiles and road vehicles to light up the path ahead. These lamps, which are usually of the acetylene type or of the electric type, give such a powerful beam that the glare is blinding to pedestrians or others getting in the range of the same. On this account several large cities and some States have passed laws and regulations, requiring the lights to be dimmed or wholly extinguished within the city limits. This is inconvenient, as a rule, with the lamps as now usually constructed and when the lamps are wholly extinguished they become useless for road lighting purposes.

It is therefore one of the principal objects of our invention to provide means whereby the light beam may be partially or wholly intercepted and shaded at the will of the operator, and to that end the invention provides a shield, which, under normal conditions, is located out of sight in some convenient part of the lamp structure, but it may be let down to a more or less degree to correspondingly cut off the light beam while permitting the remainder of the same to shine forth in its full intensity, in order that that portion of the light above the horizontal plane, which would blind a pedestrian, may be shaded without interfering with the part used to light the road ahead.

More subordinately the invention includes those novel details of construction, combination and arrangement of parts all of which will be first fully described, and then be specifically pointed out in the appended claims, reference being had to the accompanying drawings, in which:

Figure 1 is a perspective view illustrating one form of the invention, in which the shield has been let down half way. Fig. 2 is a vertical longitudinal section of the invention, with the parts in the position shown in Fig. 1. Fig. 3 is an enlarged de-

tail sectional view showing the position of the parts telescoped into the chamber body, as they normally lie. Fig. 4 is an enlarged detail view showing one way of holding the colored glass or other more or less opaque body in the skeleton frames. Fig. 5 is a detail perspective view showing the action of the spring. Fig. 6 is a detail section and plan of the same. Fig. 7 is a perspective view similar to Fig. 1, showing the shield in its closed position to completely intercept the light beam. Fig. 8 is a view similar to Fig. 2 of the parts in the position shown in Fig. 7. Fig. 9 is a detail perspective view of the chambered body, a portion being broken away for convenience of illustration. Figs. 10 and 11 are longitudinal vertical sections of modified forms of the invention.

Referring now to the drawings in which like figures and letters of reference designate like parts in all of the figures, 1 represents the lamp, which may be of any type desired, either gas, electric, or oil, etc.

2 is the usual door of the lamp and in applying our invention to the lamps now in common use on automobiles and the like, we provide a chambered body 3, having its lower half beveled as at 4 downwardly and outwardly from the horizontal pivotal axis 35 of the shield and having its upper half beveled upwardly and outwardly as at 5. The upper half of the chambered body 3 is open at the front as at 6 as best shown in Fig. 9 whereby the shield may be folded up into the upper half of the chambered body as shown in Fig. 3.

The shield, which we employ in connection with the chambered body 3, is designed to be closed over the front of the lamp to intercept the light beam and it may be constructed of one or more sections, as found convenient in practice, although we prefer to use a plurality of spherical segments consisting of skeleton frames 8 having stops 9 to limit their extendibility and provided with windows 14 of a more or less opaque substance such as colored glass, or even a relatively dark body that will entirely cut off the light, may be employed.

In the preferred form shown in Figs. 1 to 9 inclusive, the shield is of the visor-like type and is composed of a plurality of spherical segments 8 as before mentioned. The lower one of these segments is pro-

105

110

vided with a guard 20 to close the opening 6 when the shield is collapsed into the chambered member 3, the collapsing being done by means of the cable 12, which is attached to the innermost section adjacent to the shield 20 and passes over the idler rollers 10 and 11 to a convenient place adjacent to the driver and is operated by him in any suitable manner. A spring 18 is provided which continuously tends to move the shield out over the light beam. The skeleton frames 8 have their window forming elements 14 seated in recesses 13 and they may be held in place by a frame 15 and screws 16. The springs 18 are coiled around the pivot pins or bolts 7 and one end of each spring is secured at 19, while the other end is open to engage one of the frames 8, as best shown in Figs. 2, 5 and 6 of the drawings.

Many modifications of our invention may be made, without departing from the spirit of the same and for convenience of illustration, we have disclosed two such modifications in Figs. 10 and 11.

In Fig. 10, the shield 8^x is formed of a single segment and is adapted to intercept the light beam within the lamp 1^x, the shield being entirely closed within the lamp and the shield receiving chamber is formed between the reflector 21 and the body of the lamp 1^x.

In the form shown in Fig. 11, the shield 8^y is similarly mounted between the reflector 21 and the body 1^y. The door 2^y is hinged in such manner that it will let down when the shield is retracted and when the shield is moved to cut off the light beam, the shield is projected to the outside of said door instead of between the door 2^y and the reflector 21 as in Fig. 10.

We also desire it understood that the shield may be composed of any number of sections as may be found convenient in practice and the window parts 14 may be made of material of any color, either wholly opaque or partly transparent. When colored glass is used, one lamp may have red windows and the other green to give the starboard and port indications.

The further modification shown in Fig. 12, illustrates the shield 8^z, as revoluble directly about the luminant. When it is in the full line position, shown in Fig. 12, it acts as the reflector and when in the dotted line position the light beam is entirely cut off.

From the foregoing description taken in connection with the accompanying drawings, it is thought that the complete construction, operation and the many advantages of the invention will be clear to those skilled in the art.

What we claim is:

1. In a lamp construction a lamp housing,

a reflector in said housing and inclosing a light chamber, an illuminant in said light chamber, said lamp including a chamber distinct from said light chamber, and a hood pivotally mounted on said lamp and adapted to normally lie within said distinct chamber, means for projecting said hood downwardly over the front of said light chamber to cut off the light from the top of the lamp, and means for retracting said hood.

2. In a lamp construction, a lamp housing, said lamp housing including an illuminant chamber and a second chamber distinct from said illuminant chamber, a collapsible shield invisibly mounted in said distinct chamber and a device for projecting said shield into the path of the light beam, together with a device for restraining such projection.

3. The combination with a lamp housing having a door opening, and an illuminant mounted in said housing, of a structure mounted over said door opening and including a chambered body, a pivoted shield mounted for location in said body and adapted to be let down out into the path of the light beam.

4. The combination with a lamp housing having a door opening, and an illuminant mounted in said housing, of a structure mounted over said door opening and including a chambered body, a pivoted shield mounted for location in said body and adapted to be let out into the path of the light beam, means for effecting the outward movement of said shield and means for retracting said shield.

5. The combination with a lamp housing having a door opening, and an illuminant mounted in said housing, of a structure mounted over said door opening and including a chambered body, a pivoted shield mounted for location in said body and adapted to be let out into the path of the light beam, means for effecting the outward movement of said shield and means for retracting said shield, said shield including at least one spherical segment.

6. The combination with a lamp housing having a door opening, and an illuminant mounted in said housing, of a structure mounted over said door opening and including a chambered body, a pivoted shield mounted for location in said body and adapted to be let out into the path of the light beam, means for effecting the outward movement of said shield and means for retracting said shield, said shield including at least one spherical segment composed of a skeleton frame and a more or less opaque body carried thereby.

7. The combination with a lamp of a structure mounted on the lamp proper and including a chambered body, a pivoted shield mounted for location in said body

- and adapted to be let out into the path of the light beam, means for effecting the outward movement of said shield and means for retracting said shield, said shield including at least one spherical segment composed of a skeleton frame and a translucent body carried thereby.
8. The combination with a lamp housing having a door opening, and an illuminant mounted in said housing, of a structure mounted over said door opening and including a chambered body, a pivoted shield mounted for location in said body, and adapted to be let out into the path of the light beam, means for effecting the outward movement of said shield and means for retracting said shield, said shield including a skeleton frame and a light intercepting body carried thereby.
10. The combination with a lamp housing having a door opening, and an illuminant mounted in said housing, of a structure mounted over said door opening and including a chambered body, a pivoted shield mounted for location in said body and adapted to be let out into the path of the light beam, means for effecting the outward movement of said shield and means for retracting said shield, said shield including a set of spherical segments.
12. The combination with a lamp housing having a door opening, and an illuminant mounted in said housing, of a structure mounted over said door opening and including a chambered body, a pivoted shield mounted for location in said body and adapted to be let out into the path of the light beam, means for effecting the outward movement of said shield and means for retracting said shield, said shield including a set of spherical segments, each composed of a skeleton frame and a more or less opaque body carried thereby.
14. In combination with a lamp housing having a door opening, and an illuminant mounted in said housing, of a structure mounted over said door opening and including a chambered body, a shield composed of a set of spherical segments hinged to said body to collapse into the chamber thereof, or be projected over the front of said lamp to intercept the light beam in whole or in part, each of said segments including a light intercepting body.
15. A search light for road vehicles, comprising a lamp having a mouth, a structure mounted on said lamp at the mouth and including a chambered body, a shield held within said body normally out of the path of the projected beam of light, means for projecting said shield out of its chamber downwardly into the path of the beam of light to intercept said beam in whole or in part, means for retracting said shield and retaining it in its normal position and means for closing the opening in said chambered structure through which said shield is adapted to be projected, when said shield is in the retracted position.
16. In combination with a lamp case having a transparent front plate, a light deflector composed of telescoping arched sections movable about a common axis to and from a position across the upper front portion of said case, a spring for projecting the inner section, and means on the inner section for returning the remaining sections.
17. In combination with a lamp having an open side, a light deflector composed of telescoping arched sections movable about a common axis to and from a position across a portion of the open side of the lamp, the innermost section having a flange projecting across one edge of the remaining sections to move the latter in one direction when said inner section is moved in the same direction.
18. In combination with a lamp, a casing for the lamp, a light deflector composed of telescoping arched sections hingedly mounted exteriorly of the casing and provided with interengaging members for restraining relative motion between section and section when said sections are adjusted for use, and a flange on one of said sections for engaging and returning the remaining sections.
19. In combination with a lamp, a casing for the lamp, a light deflector composed of

telescoping arched sections hingedly mounted exteriorly of the casing, and provided with interengaging members for limiting the separating movements of the sections as said sections are opened up, and a flange on one of said sections for engaging and returning the remaining sections and an auto-

matic means for projecting the flanged section.
